UNITED STATES PATENT OFFICE

JOHN G. MUELLER, OF DAYTON, OHIO

METHOD OF AND MEANS FOR ABSORBING TRAIN SHOCKS FROM RAILWAY TRACKS

Application filed April 5, 1929. Serial No. 352,703.

This invention relates to the absorbing of train shocks from railway tracks.

One of the principal objects of the invention is to provide a novel method of and means for absorbing train shocks from railway tracks, which preserves the life of the track and makes for easier riding.

In the usual track construction the train shock caused by heavy and fast moving trains is transmitted through the wheels to the rails, and thence to the spikes, ties and ballast, thus racking the entire track structure. With my novel method of absorbing train shocks the line of force is transmitted from the wheels to the rails and thence to devices adjacent the rails which absorb and dissipate it.

Another object is to provide such a method and means which will be equally well adapted to different sizes and types of rails.

Further objects of the present invention will be apparent from the following description and accompanying drawings.

Obvious advantages of my method and means are—the trains will run smoother and may be operated at a higher rate of speed with decreased danger; the life of the track is preserved, thereby reducing to a minimum the cost of upkeep; and the possibility of accident due to spreading of rails, etc., is practically eliminated.

In the accompanying drawings:

Fig. 1 is a sectional elevation of a railway track with my invention applied thereto;

Fig. 2 is an enlarged detail sectional view of one rail member shown in Fig. 1 with my shock absorbing means applied thereto;

Fig. 3 is a sectional elevation of a railway track showing another form of my invention applied thereto; and

Fig. 4 is an enlarged detail sectional view of one rail member with the form of my invention shown in Fig. 3 applied thereto.

Referring to Figs. 1 and 2 of the drawings I have illustrated one form of my invention as applied to a section of the usual track arrangement of two parallel tracks 1 and 2. A tie bar or rod 3 extends beneath the track from a point beyond the outer edge of one rail to a point beyond the outer edge 50 of the other rail, and is screw-threaded

at either end, as shown at 4, to permit of adjusting the parts constituting the shock absorbing means on both sides of the base flange of each rail. The shock absorbing means are made up of a plurality of parts, one of which parts I will term a rail-bottom engaging member 5 adapted to be centrally positioned with respect to the bottom of each rail base. Each member 5 has a central longitudinal opening 6 to receive the tie rod 3 and is provided with inclined surfaces 7. On either side of each member 5 and carried by the tie rod are shock absorbing members 8 each having an opening 9 slightly larger than the opening 6 to permit of variations in track rails. The members 8 are each provided with a hook portion 10 adapted to engage the top of the rail base and with a tongue member 11 for the purpose hereinafter described. The bottom of the shock absorbing member 8 has an outwardly and downwardly inclined broad surface 12, the upper face thereof being provided with a tongue 13. A shock receiving member 14 adapted to be positioned adjacent each shock absorbing member 8 has an enlarged central portion with an elongated opening 15 to receive the tie rod 3. Extending outwardly and downwardly from the central portion of the member 14 is an arm 16 provided with a groove 17. Extending inwardly and upwardly from the central portion of said member 14 is an arm 18, the extreme upper end of which abuts against the ball of the rail when the several parts are in adjusted position with respect to each other and to the rail. The arm 18 has a groove 19 which coacts with the tongue 11 on the member 10. Nuts 20 and washers 21 are provided to hold the several parts of the shock absorbing means in position on the tie rod adjacent the rail.

When the several parts are assembled on the tie rod adjacent the rails, the inclined surfaces of each member 5 coact with inclined surfaces 22 of the members 8, the vertically elongated openings in the members 8 permitting the device to be adjusted to rails of different sizes. The groove 19 in the upper arm of the member 14 and the groove 17 in the lower member thereof coact with the 190

tongues 11 and 13 and serve as guides for the parts when being moved to adjusted positions. The movement of the arm 18 is in an upwardly directed path and urges the members 8 and 5 into engagement with the top 5 and bottom of the rail base and its upper end into engagement with the ball of the rail. The grooves 17 and 19 coacting with the tongues 11 and 13 position the members 10 against lateral displacement, while the inclined surfaces 7, 22, 23 and 24 coact to permit the several members to be brought into locked relation one with the other and with the rails 1 and 2. The washers 21 are lock washers 15 for the purpose of holding the nuts 20 in adjusted positions.

Referring to Figs. 3 and 4, I have illustrated another form of my invention in which 25 and 26 indicate parallel rails. A tie bar 20 27 extends beneath the rails from a point beyond the outer edge of one rail to a point beyond the outer edge of the other rail, and is screw-threaded at either end, as shown at 28. The shock absorbing means comprise a 25 rail supporting member 29 adapted to engage the bottom of the rail base. The member 29 has a longitudinal opening 30 to receive the tie rod 27 and inclined surfaces 31. A member 32 is provided to engage the top and edge 30 of the rail base. Coacting with these members 29 and 32 is a shock-absorbing member 33 having an opening 34 larger than the opening 30 in the member 29 to permit of adjustment of the device to rails of different sizes. 35 The member 33 has tongues 35 and 36 coacting with grooves 37 and 38 respectively in a shock receiving member 39. This member 39 has an opening 40 to receive the tie rod, such opening being considerably larger than 40 the tie rod to permit of vertical movement of said member 39. The member 39 has an arm 41 extending upwardly and inwardly to engage the ball of the rail when the device is applied. Nuts 42 and washers 43 serve to 45 maintain the several parts in adjusted position.

From the foregoing it will be apparent that train shocks imparted to the ball of a rail through the wheels may be transmitted to means contacting with the ball of the rail and thence dissipated, without injury to the spikes, ties and ballast, the dissipation of the shock further resulting in smoother running trains.

50 While the means herein described for carrying out my novel method constitutes embodiments of the invention, it is to be understood that the invention is not limited to these precise constructions, and that changes 55 may be made therein without departing from the scope of the invention which is defined in the appended claims.

Having thus fully described my invention, what I claim as new and desire to secure 60 by Letters Patent, is:

1. A device for absorbing train shocks from railway tracks comprising a tie rod, means carried by said tie rod for engaging the ball of a rail, means also carried by said tie rod for engaging the bottom of the rail base, means for engaging the top and edge 70 of the rail base, means for permitting of vertical adjustment of the means carried by the tie rod, and means for maintaining said rail base engaging means and said ball engaging means in engagement with one another and with said rail base and rail ball. 75

2. A device for absorbing train shocks from railway tracks comprising a tie rod, means carried by said tie rod for engaging the ball of a rail, means for engaging the top 80 of the rail base, triangular shaped member carried by said rod for engaging the bottom of the rail base, said several means having coacting surfaces means for preventing lateral movement of the several rail engaging means relatively to one another, means for permitting vertical adjustment of the several rail engaging means to accommodate the device to rails of different sizes, and means on the rod 85 for drawing the several parts of the device into firm engagement. 90

3. In a device for absorbing train shocks from railway tracks, the combination with a tie rod, of means carried by said tie rod for engaging the bottom of a rail base, means for engaging the top and edge of said rail base, means carried by said tie rod for engaging the ball of said rail, means carried by said rod and interposed between said ball engaging means and said rail base top and edge engaging means, means for preventing the lateral movement of said intermediate means, means for permitting of vertical adjustment of the means carried by the tie rod to accommodate the device to rails of different sizes, and means for drawing the several parts of the device tightly together. 100 105

In testimony whereof I hereunto affix my signature.

JOHN G. MUELLER.
